UNITED STATES PATENT OFFICE.

RANSOM W. DAVENPORT, OF DETROIT, MICHIGAN, ASSIGNOR TO DETROIT STOVE WORKS, OF DETROIT, MICHIGAN, A CORPORATION OF MICHIGAN.

COMBINED GAS AND COAL RANGE.

1,235,015.

Specification of Letters Patent. Patented July 31, 1917.

Application filed October 10, 1914. Serial No. 866,074.

To all whom it may concern:

Be it known that I, RANSOM W. DAVENPORT, a citizen of the United States of America, residing at Detroit, in the county of Wayne and State of Michigan, have invented certain new and useful Improvements in Combined Gas and Coal Ranges, of which the following is a specification, reference being had therein to the accompanying drawings.

The invention relates to ranges designed for use with either solid or gaseous fuel and comprises various features of construction as hereinafter set forth.

15 In the drawings:

Figure 1 is a sectional perspective view of the stove—

Fig. 2 is a longitudinal section thereof and

20 Fig. 3 is a transverse section.

Fig. 4 is a detail vertical sectional view of a mechanism adapting a gas valve and the closure of an air inlet to be operated in common.

25 A is the outer casing containing the firebox, and oven C and a closed top D provided with the usual removable lids. Adjacent to the closed top and forming an extension thereof is an open top E, beneath which is a suitable housing F for receiving the gas burners G. The oven C is heated by the gases of combustion in the fire-box B, which pass along the top flue H, down the end flue I and through the bottom flue J to the exit

35 flue K in the rear. The oven may also be heated by gas, and to this end is provided with a gas burner L arranged in the bottom portion thereof, above which is arranged a marginally perforated baffle plate M forming a false bottom.

To adapt the range so that it will operate equally well with either solid or the gaseous fuel, I have introduced various novel features as follows.—For heating the top of the stove it is essential that the space for the gas burners should be separate and distinct from the flue for the gaseous products from the solid fuel, but it is equally desirable to have a flush top for both coal-heated and gas-heated sections. I have therefore provided a sheet metal housing F which is arranged beneath the open top E and separates the same from the closed top D. The depth required for this housing F is greater than that required for the flue space between the oven and the closed top, and it is undesirable

to increase the depth of the latter space for best results. On the other hand, in heating the oven by the gas burner L it is desirable to prevent the overheating directly above the burner by the arrangement of the baffle M together with heat-insulation M' therebelow. This interposes resistance to the passage of the heat from the bottom flue J when the oven is operated by the combustion of solid fuel, which would tend to cause a relative overheating of the top of the oven.

I have overcome the difficulty by interposing above the oven a thermal insulation which will balance that below the oven, thereby preventing the abstraction of too great heat from the gases in the top flue H and thereby increasing their temperature in passing through the bottom flue J. I have also overcome the objection to the increased depth of top flue due to the depth of the housing F for the gas burner section by arranging a double flue at the top, the upper portion being for the products of combustion from the solid fuel and the lower portion constituting an exit for the gases from the burner L. Thus, as shown, N is a flue extending transversely across the top of the oven C and communicating with the space in said oven through apertures N' in the top thereof. This flue at its rear end communicates with the escape flue K, and the height of the flue above the top of the oven is such as to diminish the space between the top of the flue and the stove top to a desirable depth.

Where an oven is heated externally, as by the products of combustion from the solid fuel, any venting of the oven chamber will result in diminished efficiency. On the other hand, where the oven is internally heated, as by a gas burner, the venting is essential to the proper circulation of the gases within the oven chamber and to the supplying of oxygen to the burner for supporting combustion. I have therefore provided means for alternatively venting and cutting off draft connection to the oven, and to insure proper adjustment the vent is automatically controlled by the gas burner, so that when the latter is not in use the vent is closed but upon turning on the gas it is automatically opened. For this purpose an air chamber O is arranged in the front of the oven and is connected by a link P with the operating handle Q of the gas control valve. Whenever this valve is opened the link will

cause the simultaneous opening of the damper, while upon the closing of the valve the damper also will be closed.

In operation when the stove is used with 5 solid fuel the gaseous products of combustion will pass from the fire-box B over the flue N, down the flue I, through the bottom flue J and to the escape flue K. The interposition of the flue N between the hot products 10 of combustion and the top of the oven will prevent the overheating of the latter, and to absolutely guard against overheating thermal insulation R is also placed over the oven top. At the bottom the interposition 15 of the chamber containing the gas burner below the false bottom M will form a balancing heat-insulation, so that the top and bottom will be uniformly heated. The oven chamber is in communication with the exit flue N, but by reason of the fact that 20 the chamber O is closed air is prevented from entering the oven chamber to displace the heated air. Thus in effect there is a closed oven chamber. When gas is used for 25 fuel the turning on of the valve Q will open the chamber O, so that air is applied to the burner, and the hot gases are permitted to pass around the baffle M through the oven chamber and finally out through the flue 30 N to the escape flue K.

It will be observed that there is no communication between the surrounding flues for the gaseous products from the solid fuel and the interior of the oven. It will also be observed 35 that the gas burner is in the oven and that the air for supporting combustion comes from outside the stove and not through the surrounding flues. This prevents any interference with the efficiency of the coal stove by reason of the gas burner, 40 or of the gas heater by reason of the adaptation for use of solid fuel.

The gas heated top is also entirely independent of the coal heated top, but the extent 45 of the former is such as to partially overlap the oven. Interference with the oven flues is prevented by dropping the oven so as to provide clearance beneath the housing or pan for the gas burners, and, as has been described the flue beneath the coal heated top is restricted in depth by the transverse flue N above the oven. Thus 50 without increasing the height of the stove or changing the plan of the coal and gas heated tops I have obtained the necessary 55 depth for the housing of the gas burners without interference with the oven or its surrounding flues.

What I claim as my invention is:—

60 1. In a cooking range, the combination with a casing having adjacent top sections respectively heated by solid and gaseous fuel, of a housing beneath the gas-heated sec-

tion, an oven within said casing overlapped by said housing and arranged therebeneath to form a flue therebetween, a firebox adjacent to said oven, and a casing above said oven adjacent to said firebox deflecting the gases from the fire box into proximity with the stove top, said casing 70 forming a transversely-extending escape flue connected with said oven chamber.

2. In a cooking range, the combination with an oven, of a casing containing a firebox and providing flues surrounding the 75 oven, a false bottom in said oven, a burner arranged beneath said false bottom and between the same and the bottom portion of the surrounding flue, a casing above said oven forming a thermal insulation between 80 the oven and the top portion of the surrounding flue, a housing adjacent the stove top spaced from the oven by the top portion of the surrounding flue, said flue being offset downwardly between said housing and 85 the casing above the oven, and a gas burner in said housing.

3. In a cooking range, the combination with a casing having adjacent top sections, respectively heated by solid and gaseous 90 fuel, of a housing beneath the gas-heated section, an oven within the casing overlapped by said housing and arranged therebeneath to form a flue therebetween, a firebox adjacent to said oven, a casing above 95 said oven adjacent to the fire-box for diminishing the flue-space beneath the coal-heated top, said casing forming a thermal insulation above the oven and forming an escape flue for the oven gases, and a thermal insulation at the oven bottom substantially counterbalancing that above the oven.

4. In a cooking range, the combination with a casing having adjacent top sections respectively heated by solid and gaseous 105 fuel, of a housing beneath the gas heated section, an oven within said casing overlapped by said housing and arranged therebeneath to form a flue therebetween, said flue having a portion extending beneath 110 the oven, a fire box with which said flue communicates, and a casing above said oven, serving the triple functions of an escape flue for the gases from the oven burner, a means for deflecting the gases from the fire 115 box into proximity to the stove top, and a thermal insulation substantially counterbalancing that formed between the oven bottom and false bottom.

In testimony whereof I affix my signature 120 in presence of two witnesses.

RANSOM W. DAVENPORT.
